UNITED STATES PATENT OFFICE.

MARK B. FERMANIAN, OF TROY, NEW YORK.

TIME-CONTROLLED DRAFT REGULATOR.

Application filed April 10, 1922. Serial No. 551,112.

To all whom it may concern:

Be it known that I, MARK B. FERMANIAN, a citizen of Armenian Republic, residing at Troy, in the county of Rensselaer and State 5 of New York, have invented new and useful Improvements in Time-Controlled Draft Regulators, of which the following is a specification.

This invention relates to a time controlled 10 device for regulating the draft of a stove, range, furnace, or the like and the object is to provide in connection with a clock mechanism, a device serving to mount the clock and to enclose the operative elements connected by flexible devices with the dampers and draft slides of the heating apparatus.

A further object is to provide a controlling 20 device which is under the control of the clock mechanism, and which shall include an actuating arm adapted to be thrown by a spring when released by a trip or trigger operated by the alarm mechanism of the clock.

A still further object is to provide particular means for rendering the alarm mechanism effective for the purpose stated, and for discontinuing the operation of the alarm mechanism when the actuating arm above mentioned has been released.

With the foregoing and other objects in 30 view the invention consists in the novel construction and arrangement of elements described and claimed, it being understood that modifications in the construction may be made within the scope of the claims without departing from the spirit of the invention.

In the drawings, Figure 1 is a perspective view showing the apparatus as applied to a kitchen range; Figure 2 shows a hot air furnace in side elevation and the draft controlling devices properly positioned and connected; Figure 3 is a front elevation of the operative mechanism, the door of the casing therefor being open; Figure 4 is a horizontal section, on line 4—4 of Figure 3; Figures 5, 45 6, and 7 show details of construction; Figure 8 shows a modified casing within which the clock is fully inclosed, together with other mechanism not appearing in this view but shown in Figure 3.

50 A casing 10 is mounted or supported in any suitable manner, as by securing the same to the wall of a room by means of screws 11 and 12. The casing includes a rear wall 13 cut away as shown at 14, and further includes a door 15 hinged to the casing and provided with a cut away portion 16, corre-

sponding with the cut away portion of the rear wall of the casing.

The clock 18 may be of standard type, a 60 clock provided with an alarm mechanism being required. That element of the alarm mechanism projecting from the casing and usually serving as the hammer for sounding the bell, is indicated at 19, and in this instance serves as a member of the releasing 65 mechanism. The casing of the clock carries curved outwardly projecting and offset elements 21 and 22 which may be termed hooks, these elements engaging the apertures 23 and 24 in the flanged portions 25 and 26 of 70 the casing, thereby serving to retain the clock with the lower portion of the casing in direct cooperation with the cut away portion of the door and the rear wall of the casing. The door is provided with a flange 75 26' on the edge opposite the hinged portion, this flange serving to fit over one side wall of the casing and retain the door in closed position.

The actuating arm 30 is pivoted at 31 on 80 the rear wall of the casing, and connected with the end 32 of this arm is a spring 33 secured to the wall of the casing at the point 34. The end 32 of the arm 30 is provided 85 with a notch as shown, and this notch is engaged by a trip or trigger 35 pivoted at 36 and having its lower end drawn towards the right as shown in Figure 3 by a spring 37.

This trip 35 is provided with a lower 90 curved portion 38 engaged by the curved portion 39 of arm 30 so that upon downward movement of the arm 30 the lower end of the trip may be thrown outwardly towards the left and the end of the arm clear the 95 trip so that the notch at the end 32 is engaged in the manner shown in Figure 3. The upper offset end 40 of the trip 35 is directly in the path of movement of the element 19 of the alarm mechanism, and when the element 19 is set in operation at the time for 100 adjusting the draft elements, the trip is thrown out of engagement with the actuating arm 30, the elements 35 moving about its pivotal point in this operation.

In setting the device for operation the actuating arm is drawn downwardly at the left and the spring 33 thereby placed under tension, so that upon the release of the trip, the arm 30 moves under the influence of the 110 spring 33, the left hand end of the arm moving upwardly and producing tension on certain flexible devices for controlling the

draft elements in the manner indicated below.

- An adjustable stop 42 contacts with the trigger at points 43 and serves an obvious purpose. A hammer retaining device includes a rod 44 having an upper off set end 45 adapted to engage the hammer 19 after the latter has imparted a blow to the trigger for releasing the actuating arm 30. The lower end of the rod 44 is pivotally connected at 46 to the arm 30, so that after the device has been operated the element just described serves to automatically discontinue the operation of the alarm mechanism.
- Connected with the left hand end of the arm 30 is a rod or wire 48 provided with a loop or ring 49 having connection with a chain or other flexible device 50. This chain 50 includes a ring 51 and an additional ring 52 at the extreme end thereof. The right hand end of the arm 30 is connected with a chain 53 having a hook 54 or other engaging device on the end thereof. This chain last named may pass out of the casing through the side aperture 55 or through lower aperture 56, depending upon the exact use to which the device is put, that is whether applied to the draft elements of a kitchen range or to the corresponding elements of a hot air or other furnace. A guiding device 56 mounted on the rear wall of the casing accommodates the chain 53, and other guiding devices may be provided if required.
- In applying this device to a kitchen range, the chain 53 may be connected by means of hooks 54 with the damper in the pipe, this damper being designated 60. The chain 50 may pass around a pulley, the loop or ring 51 then engaging the operating device of the lower draft slide 62. The chain then passes upwardly and the element 52 is connected with the operating device of the check draft slide 63. This arrangement is effective when the device is connected with a stove or range of the type shown in the drawings, and it is obvious that when the upper and lower draft slide are both on the front of the range or both on the one side thereof, a slightly different arrangement of the chains and pulleys will be required, it merely being necessary that the chain 50 be connected with both slides in exactly the manner indicated.
- In applying the device to the draft element of a hot air furnace of the type shown in outline in Figure 2, the chain 53 is made somewhat longer and passes through the

lower aperture 56 of the casing, the extreme end of this chain having connection with the draft slide 66. The other chain 50 may pass over pulleys 67 and 68 and drop downwardly to a point of connection with the check damper 69, so that both the draft elements will be controlled at the same time.

Having thus described my invention I claim:

1. A device of the class described, comprising a clock including an alarm mechanism, a pivoted actuating arm, flexible devices connected therewith on opposite sides of the pivotal point and adapted for connection with the draft elements of a heating apparatus, a spring for throwing said arm, a pivoted trip for engaging one end of the arm and retaining the latter with the spring under tension, the release of the trip serving to release the arm and operate the draft elements through the flexible devices, one end of the trip being engaged by an element of the alarm mechanism, an engaging device formed on one end of the arm and said arm acting to throw the trip away from the arm and out of the path thereof when placing the spring under tension, the trip then contacting with the engaging device for retaining the arm and a rod pivotally connected with one end of the actuating arm and including an offset member movable into engagement with said element of the alarm mechanism for rendering the latter inactive.

2. A device of the class described comprising a pivoted actuating arm, a spring for throwing said arm, flexible devices connected with opposite ends of the arms and adapted for connection with the draft elements of a heating apparatus, a trigger for retaining the arm in position with the spring under tension, the trigger being pivoted at the point intermediate of its ends, a spring for retaining the trigger in operative position, the upper end of the trigger including an offset portion, a clock including an alarm mechanism, one element of which is positioned for imparting a blow to the trigger on the offset end thereof upon the operation of the alarm, a stop for limiting the movement of the trigger, and a device operated by the release of the actuating arm for retaining the alarm mechanism inactive and acting to obstruct the path of movement of said element of the alarm mechanism, and prevent impact on the trigger.

In testimony whereof I affix my signature.

MARK B. FERMANIAN.
